UNITED STATES PATENT OFFICE.

MADISON W. REEVES, OF SAYRE, PENNSYLVANIA.

DESIGN FOR A BANANA-STAND.

SPECIFICATION forming part of Design No. 33,265, dated September 25, 1900.

Application filed August 30, 1900. Serial No. 28,609. Term of patent 7 years.

To all whom it may concern.

Be it known that I, MADISON W. REEVES, a citizen of the United States, residing at Sayre, in the county of Bradford and State of Pennsylvania, have invented a new and original Design for Banana-Stands, of which the following is a specification.

My invention relates to designs for banana-stands, which is illustrated in the accompanying drawings, in which—

Figure 1 is a side elevation of a banana-stand embodying my invention. Fig. 2 is a top plan view of the same.

My design consists of a base portion having a top or table portion A and from which projects a central standard B. Below the table A a plurality of inclined legs C have their upper ends connected with the standard B and radiate therefrom, as shown. Projecting from the under side of the table A are the braces D, which have their upper and lower

ends, respectively, in engagement with the table and the inclined legs C. Supported at the top of the standard B is a cap E, and radiating from the under side of this cap are a plurality of arms F. Extending inward at an inclination and connecting the arms F at points between their ends and the standard B are the braces G.

Having thus described my design, what I claim, and desire to secure by Letters Patent, is—

The design for a banana-stand substantially as herein shown and described.

In testimony whereof I have hereunto set my hand in the presence of two subscribing witnesses.

MADISON W. REEVES.
